STEP STOOL

Leopold Durko, Arlington Heights, Ill., assignor to Comfort Lines, Inc., Chicago, Ill., a corporation of Illinois

Application February 23, 1954, Serial No. 29,176

Term of patent 3½ years

(Cl. D15—8)

To all whom it may concern:

Be it known that I, Leopold Durko, a citizen of the United States, residing at Arlington Heights, in the county of Cook and State of Illinois, have invented a new, original, and ornamental Design for a Step Stool, of which the following is a specification, reference being had to the accompanying drawing, forming part thereof.

Fig. 1 is a perspective view of a step stool embodying my new design.

Fig. 2 is a rear elevational view of the step stool.

I claim:

The ornamental design for a step stool, substantially as shown.
